INVENTOR

ATTORNEY

UNITED STATES PATENT OFFICE.

EDWARD SWEENEY, OF NORRISTOWN, PENNSYLVANIA.

ARTIFICIAL LIMB.

1,268,642.

Specification of Letters Patent. Patented June 4, 1918.

Application filed July 10, 1917. Serial No. 179,716.

To all whom it may concern:

Be it known that I, EDWARD SWEENEY, a citizen of the United States, residing at 762 Kohn street, Norristown, in the county of 5 Montgomery and State of Pennsylvania, have invented new and useful Improvements in Artificial Limbs, of which the following is a specification.

The invention relates to artificial limbs, 10 and has for an object to provide an artificial limb particularly embodying a foot portion, which can be easily applied; consists of few and simple parts that will not readily wear out; will afford ease in walking, and 15 furthermore, is so arranged and constructed that when a shoe is subsequently fitted over the foot portion, the disability of the person having the artificial limb will not be noticed in walking, and the entire arrangement will present a neat appearance; the 20 artificial limb furthermore embodying suitable cushioning means whereby to afford ease in manipulation, and a natural movement to the artificial foot portion.

25 The invention embodies among other features an artificial limb adapted to what is known as the "Chopart" construction, in which the foot portion having previously been severed from the limb, leaving merely 30 a stump at the lower part, permits of the adaptation of my particular form of foot element to the amputation, in order to effect the desired result.

In the further disclosure of the invention 35 reference is to be had to the accompanying drawings, constituting a part of this specification, in which similar characters of reference denote corresponding parts in all the views, and in which—

40 Figure 1 is a side elevation showing my device applied to a limb.

Fig. 2 is a vertical sectional view taken through the structure shown in Fig. 1.

Fig. 3 is a horizontal sectional view taken 45 on the line 3—3 of Fig. 1.

Fig. 4 is a horizontal sectional view taken on the line 4—4 of Fig. 2.

Referring more particularly to the views I disclose a limb 10 of a person from which 50 the foot has been severed at the lower part, namely, at the point 11, this being what is known as the "Chopart" construction, leaving the stump 12 of the limb. The invention consists more particularly of a sole 55 or bottom 13 of rubber or leather, said sole

underlying a flat spring plate 14 at the rear end of which is a transverse hinge 15 to which is pivoted a heel plate 16, carrying a cushion 17 which may be better termed a heel cushion, and upon which the stump 60 12 repose. An aluminum toe casing 18 is suitably secured to the spring plate 14, as shown, and within the same at the toe end is arranged a toe cushion 19, made of some kind of sponge rubber or the like, an aluminum arch 20, preferably solid, being also arranged within the casing 18, and formed with a vertical curved limb-embracing portion 21, secured by suitable straps 22, said portion 21 being hinged at 15. An interposed layer of some soft material, such as 65 cotton, indicated by the numeral 23, is arranged between the arch portion 20 and the lower part of the limb 10 in order to reduce to a minimum any friction, and cushion 70 the limb against the inner part of the arch.

It will be noted that the toe cushion 19 projects out beyond the front end of the toe casing 18, in order that a bending movement can be obtained at this point, and it will also be seen that the rear end of the casing 18 at the point where it meets the limb-embracing portion 21, is encircled 75 by an interfitted rubber or other flexible 80 band 24.

With the construction set forth, it will be seen that the foot described can readily be used in the same manner as the natural foot, allowing the bending at the forward part of 90 the heel, and along the line where the foot ordinarily would bend in walking, so that the foot can be raised along the toe, and then re-deposited upon the ground with the heel first in the natural manner. It will be 95 seen that the forward part of the arch 20 repose within the rubber toe cushion 19 so as to give a cushioning effect against the limb during the walking action. The plate 14 may be suitably ribbed, as shown at 25, in 100 order to make it as light as possible, and at the same time give it the required elasticity or flexibility and it will be clearly seen that with a construction of this character, there will be no material noise in the walking operation, due to the cushion sole 13 which is beneath and covers the flexible plate, and in fact is vulcanized or otherwise secured thereto.

From the foregoing description, it will be 110

apparent that the device described consists of few and simple parts, can be cheaply manufactured, and when properly applied to the amputated limb will afford the desired result.

5 It will of course be understood that I do not limit myself to the particular form of securing means for holding the artificial limb on the natural limb, and that various 10 slight changes may be made without departing from the spirit of the invention, the scope of which is defined in the appended claims.

Having described my invention I claim:

15 1. In a device of the character described, the combination with a flexible sole portion, of a toe casing attached to the sole portion, a cushion in the toe casing, an arch pivoted to the sole portion and extending into the 20 toe casing to coöperate with the cushion therein, an attaching member formed with the arch, and a cushioned heel portion.

25 2. In a device of the character described, the combination with a flexible sole portion, of an underlying cushion sole, a toe casing attached to the sole portion, an arch pivoted to the sole portion, an attaching member projecting upwardly from the arch, means for permitting of a bending movement between the attaching member and arch, and a

cushion in the toe casing and having the arch associated therewith.

3. In a device of the character described, a flexible ribbed sole portion, a toe casing therefor, a combined arch and attaching 35 plate pivoted to the sole portion, a cushion in the toe casing and engaged by the arch, and a heel cushion on the rear end of said sole portion.

4. In a device of the character described, 40 the combination with a flexible sole portion, of a toe casing attached thereto, an arch pivoted to the sole portion and projecting into the toe casing, and a cushion in the toe casing and having one portion engaged 45 by the forward part of the arch, and the other portion projecting beyond the front end of the toe casing.

5. In a device of the character described, the combination with a flexible sole portion 50 including a pair of hingedly connected plates, a toe casing therefor, an arch pivoted at the point of pivotal connection of said plate, an attaching plate associated with the arch and means for establishing a bending 55 movement between the arch and said attaching member.

In testimony whereof I affix my signature.

EDWARD SWEENEY.
